Primary Examiner — Kevin Rudzinski(74) *Attorney, Agent, or Firm* — Shumaker & Sieffert,
P.A.(57) **CLAIM**

The ornamental design for a display screen with graphical user interface, as shown and described.

DESCRIPTION

FIG. 1 shows a front view of a display screen with graphical user interface, showing a first embodiment.

FIG. 2 shows a front view of a display screen with graphical user interface, showing a second embodiment.

FIG. 3 shows a front view of a display screen with graphical user interface, showing a third embodiment.

FIG. 4 shows a front view of a display screen with graphical user interface, showing a fourth embodiment.

FIG. 5 shows a front view of a display screen with graphical user interface, showing a fifth embodiment.

FIG. 6 shows a front view of a display screen with graphical user interface, showing a sixth embodiment.

FIG. 7 shows a front view of a display screen with graphical user interface, showing a seventh embodiment; and,

FIG. 8 shows a front view of a display screen with graphical user interface, showing an eighth embodiment.

The broken lines in the drawings illustrate the display screen and portions of the graphical user interface and form no part of the claimed design.

1 Claim, 8 Drawing Sheets(56)
